UNITED STATES PATENT OFFICE.

HUBER R. DAVIS, OF CARDINGTON, OHIO.

INCUBATOR.

SPECIFICATION forming part of Letters Patent No. 519,244, dated May 1, 1894.

Application filed August 31, 1893. Serial No. 484,459. (No model.)

To all whom it may concern:

Be it known that I, HUBER R. DAVIS, a citizen of the United States, and a resident of Cardington, in the county of Morrow and State of Ohio, have invented certain new and useful Improvements in Incubators; and I do declare the following to be a full, clear, and exact description of the invention, such as will enable others skilled in the art to which it applies to make and use the same, reference being had to the accompanying drawings, and to letters of reference marked thereon, which form a part of this specification.

Figure 1 is a front elevation of incubator, with door of egg chamber open, and runway extended and unfolded. Fig. 2 is a side elevation of incubator. Fig. 3 is a plan view, with both covers removed. Fig. 4 is a section on the line $x-x$, Fig. 1. Fig. 5 is a longitudinal section through egg holder, and turner. Fig. 6 is an elevation of the rear end piece of runway. Fig. 7 is a perspective view of water pan and pivoted support, with heating pipe shown extended down into pan.

This invention has relation to certain new and useful improvements in incubators, the objects being, first, to provide an improved arrangement and construction of means for supplying the necessary heat; second, to improve the construction and arrangement of the egg chamber and egg holding and turning devices; third, to provide a brooder in connection with the incubator, and finally to improve the general arrangement and construction of parts, as will hereinafter appear.

With these objects in view the invention consists in the novel construction and combination of parts all as hereinafter described and pointed out in the appended claims.

Referring to the accompanying drawings, the letter A designates the frame or casing of the incubator, having a removable or hinged cover B.

C designates a lamp support or chamber located centrally underneath the bottom of the frame or case A and C' is a lamp therein.

D designates a heater having a double or hollow wall which forms a receptacle d for water or other heat circulating medium. This receptacle surrounds both at the sides and at the top a central chamber D', which gradually tapers or increases in diameter from its

lower open end upward in the form of an inverted frustum of a cone, and causes a corresponding decrease in the capacity of the chamber d from its lower end upward. The heat from the lamp is conducted into the chamber D', whose peculiar form, as above described, not only offers an increased heating surface, but also causes the water in the chamber d to become more highly heated, owing to the gradually diminishing sheet or layer thereof present in the said chamber. Leading outward from the upper portion of said chamber d are four pipes or tubes a which extend underneath the case A, one to each corner portion thereof, from whence they extend upward to the upper portion of the case, and terminate each in an inward horizontal arm a', which discharges into a tank E. At the central portion of said tank is an opening b which communicates with a pipe E', leading to the front of the case and thence downward and discharging into the lower portion of the chamber d. The capacity of the pipe E' should equal the combined capacities of the pipes a. Said pipes a enter the tank at the corner portions thereof, and extend toward the center. This arrangement of pipes, it will be seen, affords means for a continuous circulation, the cooler water passing to the center of the tank and back to the heater, while the more highly heated water is at the corner portions of the tank and in the pipes a.

E² designates a removable cover for the tank, said cover having flanges at its edges which fit over the edges of the tank. The cover E² has a hollow tubular projection e, which projects out through the cover B of the case, and has a screw cap e' which may be removed for filling.

c is a pipe which extends from the heater to the side of the case, and provides means for drawing off the water from the heater.

F designates the egg chamber which is situated in the upper portion of the case A, below the tank E, which forms the top to said chamber, and F', F' are egg trays supported in said chamber. In the drawings I have shown a machine having two egg trays but it will be understood that I may use as many of these trays as may be desired. The trays F', F' are preferably made of metal so that they

will not warp or swell, and thereby cause them to bind or stick on the guides or ways upon which they slide. The bottoms of the trays are slotted and are covered with cloth f' , or 5 other yielding material. The egg turners F^2 are also of metal, preferably, and consist each of a rectangular frame resting upon flanges f^2 of the trays, and free to move thereon. The filling for the trays consists of wires g , 10 crossing each other at right angles, and leaving openings for the eggs. At each point where the wires cross each other they are soldered together, thus giving them the necessary strength. At the same time they are 15 more yielding than wooden or other rigid strips. Wire is also preferred for the purpose in that it gives the frames greater capacity. On each frame is a projection or lug g' which is designed to be engaged by a 20 crank g^2 of a rock shaft G which extends transversely over the tray, and extends through the casing at one end where it is provided with an operating crank. Each tray is provided preferably with its own rock shaft, as 25 shown in the drawings. The operations of these shafts impart a longitudinal movement to the turners, and cause them to turn the egg. The egg trays may be readily removed without interfering with said shafts. The 30 pipes a where they pass through the egg chamber are exposed, and as they are at the corner portions of said chamber they supply the heat where it is most desired. Underneath the egg trays are four evaporating pans 35 H , one in each corner portion of the chamber, and supported each upon a pivotal block H' . Leading from each pipe a is a small pipe h which extends to the pan H at that portion of the chamber, and has its closed end 40 portion bent downwardly therein, as seen at h' . These pipes are kept heated by the hot water from the pipes a , and serve to heat the water in the pans, thereby providing for the evaporation of a sufficient amount of moisture in the chamber. By swinging the blocks 45 H' on their pivots from underneath the pans, the latter may be readily removed for filling, more or less water being placed therein as may be desired. 50 i designates a series of small openings leading outward through the walls of the chamber F , and closed by small pivoted slides i' on the outside of the case. These openings provide means for quickly lowering the temperature of the egg chamber should it be desired. 55 I is a door to the egg chamber at the front, and I' , I'' are smaller doors at the sides. These doors are shown as having glass covered openings I^2 . Each of said doors is made to seat flush into the casing in a tight manner. 60 J designates the brooder chamber which is situated directly underneath the egg chamber. Said chamber is heated by the pipes a which are exposed where they pass the chamber, and also by heat radiated from the heater D , and entering the chamber through an

opening j in the bottom thereof. There is a door J' at each end of said brooding chamber, one of said doors having a glass covered opening. 70

K is a false bottom for the brooding chamber, said bottom being removable through one of the doors J' . Said bottom has an opening k therein arranged to register with the opening j . 75

L designates a run-way attachment for the brooding chamber, said attachment comprising a bottom board l , which is attached to the door J' , side pieces l' hinged to said bottom board and adapted to fold thereon, an end piece l'' hinged to the door, and a rear end piece l^3 . The part l^3 is not hinged to the bottom board, but is removably supported thereon, and held by the pressure of the sides l', l'' 85 against cleats or blocks l^4 thereon.

When not in use, the side pieces and end pieces are folded down onto the bottom piece, and the whole, together with the false bottom K , placed in the brooding chamber. The end 90 piece l^3 in folding is removed and placed upon the bottom in the manner shown in Fig. 4.

When it is desired to use the attachment, the door J' is removed, bringing with it the run-way; the side and end pieces are adjusted, and the rear end of the bottom board l is 95 inserted into the opening for the door. The forward end is supported by legs m which are pivoted to the attachment at their upper ends, and when not in use fold up alongside 100 of the lateral edges of the board l .

Openings n in the rear end board l^3 permit the chickens to pass from the brooding chamber to the run-way. A slide M is provided to close said openings n when it is desired to 105 shut the chickens within the brooding chamber. The said slide is shown as consisting of a strip working in guides M' on the said end piece, and having an opening n' designed to register with one of the openings n . The 110 slide is short enough when in such position to leave open the other opening. The exact arrangement and combination of the slide is however not essential.

The false bottom K may be readily removed 115 and cleaned.

The manner of heating the egg chamber as above described, is particularly effective, for the reason that the location of a heating pipe at each corner portion thereof insures the 120 heating of all portions of the chamber alike.

Suitable heat regulating devices, not shown, may be employed.

The heat utilized in heating the brooding chamber, as described, would otherwise be 125 radiated off and lost.

Having described my invention, what I claim as new, and desire to secure by Letters Patent, is—

1. In an incubator, the combination with 130 the case having the egg-chamber F situated in the upper portion of said case, of the tank above said egg chamber, the brooding chamber J immediately below said egg chamber,

- the heater underneath said brooder, an air passage from said heater into said brooder, hot water pipes leading from said heater and extending up through the corner portions of 5 the said case and discharging into said tank, said pipes being exposed when they pass through said brooding and egg chambers, a return pipe leading from the center of said tank to the lower portion of said heater, 10 evaporating pans in said egg chamber, and connections with the water pipes for supplying heat to said pans, substantially as specified.
2. In an incubator, the combination of an egg chamber, a tank above said chamber, a heater below said chamber, a pipe leading from said heater upward through each corner portion of said chamber and entering said tank, a return pipe from said tank to the 15 heater, evaporating pans in said egg chamber, and pipes leading from the corner pipes into said pans, substantially as specified.
3. In an incubator, the combination with the case, the tank at the upper portion of said 20 case, and the egg chamber underneath said tank, of the heater D below said egg chamber, said heater having a water chamber d, surrounding a central heating chamber D', said heating chamber D' increasing in diameter from its lower end upwardly, and causing a corresponding decrease in the diameter 25 of the chamber d, a system of hot water pipes leading from the upper portion of said chamber d through the corner portions of the egg 30 chamber to the said tank, and a return pipe from said tank to said chamber, d, substantially as specified.
4. In an incubator, the combination with an egg chamber, and egg trays therein, of a series of hot water pipes extending through the corner portions of said chamber, a series of water pans underneath said trays, and pipes leading from said hot water pipes into said 35 pans, substantially as specified.
5. In an incubator, the combination with an egg chamber, and the hot water pipes leading therethrough, of a series of open pans therein, movable supports for said pans, and pipes leading from said hot water pipes to said pans, 40 substantially as specified.
6. In an incubator, the combination of an egg tray having a slotted bottom, a yielding covering for said bottom the egg turner slidably supported in said tray, and consisting of 45 a rectangular frame and a filling composed of wires crossing each other at right angles and

fastened to each other at each point of crossing, the meshes of said filling being sufficiently coarse to receive the eggs, a lug or projection g' on the said frame, and a crank- 60 shaft having a crank arranged to engage said lug, whereby said turner may be reciprocated, substantially as specified.

7. In an incubator, the combination with a brooding chamber, of a run-way attachment, 65 said run-way having a bottom portion, legs adapted to fold up against said bottom portion, and sides and ends adapted to be assembled upon said bottom portion in compact arrangement whereby when the device is not in 70 use, it may be slid into and contained within said chamber, substantially as specified.

8. In an incubator, the combination with a brooding chamber and a door therefor, of a run-way attached to said door, said run-way 75 comprising a bottom board, side pieces l', l'', hinged to said bottom board, an end piece l'', a rear end piece l'', having openings therethrough, a slide arranged to close said openings when desired, and legs, said legs and side 80 pieces, and the end piece l'' being arranged to fold upon and against the bottom piece, the end piece l'', and its slide being removable, and capable of being placed in compact position upon said bottom piece whereby the entire run-way may be slid into and contained 85 in said brooding chamber, substantially as specified.

9. An incubator and brooder comprising essentially the case A, the tank at the upper portion of said case, the egg chamber underneath said tank, the egg holding and egg turning devices, the brooding chamber immediately below said egg chamber, the run-way having folding sides, ends and legs and normally contained in said brooding chamber, the heater below said brooding chamber, the hot-water pipes leading from the water chamber of said heater up through the corner portions of said case, said pipes being exposed where they 90 pass through said brooding and egg-chambers, the evaporating pans in said egg-chamber, the closed pipes leading from the hot-water pipes to said pans, and a return pipe from the said tank to the heater, substantially as specified. 100

In testimony whereof I affix my signature in presence of two witnesses.
